(57) **CLAIM**

The ornamental design for a ring sizer, as shown and described.

DESCRIPTION

FIG. 1 is a front perspective view of a ring sizer.

FIG. 2 is a rear perspective view of the ring sizer opposite from FIG. 1.

FIG. 3 is a top view of the ring sizer.

FIG. 4 is a bottom view of the ring sizer.

FIG. 5 is a side view of the ring sizer.

FIG. 6 is a front view of the ring sizer; and,

FIG. 7 is a rear view of the ring sizer.

The broken lines depict portions of the article that form no part of the claimed design.
